UNITED STATES PATENT OFFICE

RANSOM A. BARNES, OF ANTIOCH, CALIFORNIA

DESIGN FOR A STERILIZER KIT

Application filed July 23, 1931. Serial No. 40,638. Term of patent 7 years.

To all whom it may concern:

Be it known that I, RANSOM A. BARNES, a citizen of the United States, residing at Antioch, in the county of Contra Costa and State of California, have invented a new, original, and ornamental Design for a Sterilizer Kit, of which the following is a specification, reference being had to the accompanying drawings, forming part thereof.

Figure 1 is a perspective view of a sterilizer kit, showing my new design, and Figure 2 is an end view.

I claim:
The ornamental design for a sterilizer kit, as shown.

RANSOM A. BARNES.
